UNITED STATES PATENT OFFICE.

LANK HUGHES, OF WASHINGTON, DISTRICT OF COLUMBIA.

SNOWPLOW.

Application filed March 31, 1924. Serial No. 703,232.

This invention relates to machines for removing and clearing snow from railroads, street car lines and other roadways. In fact this machine may be used for the clearing 5 of snow from any street, roadway or surface from which it is desirable to remove the snow. It relates more specifically to that form of machine adapted to scoop up the snow by a forward extending scoop and 10 distribute it to both sides of the machine or to either side thereof as the operator may desire.

Another object of this invention is to provide a snow machine in which the front 15 end of the scoop is pivotally connected to the scoop proper and supported in such a way that the scoop may always be in operating contact with the surface from which the snow is to be removed, though the supports therefor may be elevated or depressed 20 by any unevenness of the surface over which the scoop is operated.

It is another object and purpose of this 25 invention to provide a snow removing machine in which the parts are simple and compactly related so they may be operated by a person from one position.

It is another object of this invention to 30 provide a machine that embodies its own motive power or that may be attached to the front part of some other machine having a suitable motive power, such as a truck, tractor or railroad locomotive. For the purpose 35 of operating applicant's device on track ways, the supporting wheels may be provided with flanges for holding the machine on the track.

These and other advantages will appear 40 from the description in connection with the drawings in which:—

Figure 1, is a top plan view of the machine as a whole showing in dotted lines the propelling means.

Figure 2, is a side elevation of the machine as shown in Figure 1.

Figure 3, is a front elevation showing the snow scoop and the chutes located on the sides thereof for directing the snow to each side.

Figure 4, is a rear elevation showing the operator's cab and the chutes.

Figure 5, is a bottom plan view showing the connection between the scoop and the snow blade and the snow deflecting wings.

Figure 6, is a section on the line 6—6 of Figure 5.

Figure 7, is a section on the line 7—7 of Figure 5.

Figure 8, is a section to the section similar to that of Figure 7, but showing the blade 60 bent up.

Figure 9, is a view showing how the spring is bent when the blade is deflected.

Figure 10, is a section on line 10—10 of Figure 5. 65

Figure 11, is a section on line 11—11 of Figure 2.

Figure 12, is a section on line 12—12 of Figure 2.

Figure 13, is a view of one of the chutes 70 showing the lever mechanism for operating the snow deflectors on the outer ends of the chutes.

Figure 14, is a sectional view of the snow deflector open for throwing the snow down 75 as it leaves the chutes.

Figure 15, is a modified form of snow scoop.

Figures 16 and 17 are detail views of the 80 runners on the front of the scoop blade.

In the figures of the drawings similar reference characters are used to designate like parts of the machine.

The reference character A, is used to designate the machine as a whole. The machine 85 is here shown as supported by four wheels, two rear traction wheels B and two front wheels C, adapted to control the direction or motion of the machine and steered by a steering wheel 12' as in motor vehicles. 90 Any suitable motive power may be used but in this instance we have represented diagrammatically a gasoline motor indicated by the reference character D but any other suitable motive power may be used. The 95 machine may be pushed by a tractor, truck or by a locomotive. In case some external motive power is used, the motive power represented by the character D may be dispensed with or permitted to remain idle. 100 The form of motive power is no part of this invention. The reference character 1 represents the frame suitably supported by the before described rear and front wheels. Upon the frame are located the housing or 105 cab 2, the scoop 3 and the scoop controlling mechanism, the chutes 4 on each side of the cab and the operating mechanism for directing the course of the machine and for operating the snow removing parts. All 110 parts of the mechanism are adapted to be operated by an operator situated within

the cab. On the front part of the machine and supported by the frame 1 is an inclined V shaped scoop having its large part toward the front for scooping up the snow. 5 On the front end of the scoop, there is a pivotally attached blade 5, while on each side thereof, there is a snow wing 6, the snow wings are somewhat formed in the shape of a roll, wide at the top and narrow 10 at the bottom, for guiding the snow from the front end of the scoop to the rear and upper end thereof and into the chutes 4. In normal working conditions, as shown in Figure 3, the snow will be parted at the 15 upper end of the scoop, part going to the right side or chute and part to the left side or chute of the machine. But if it should be desired to direct the snow into one chute, one of the wings will be rotated 20 beyond the opening of one chute and into line with the walls of chute into which the snow is to be directed. The mechanism for rotating the wings is specifically shown in Figure 11. 25 The scoop blade 5 with its specific operating and hinge structure is specifically shown in Figure 5. To the central rear part of this blade, a lever 8 is suitably attached. Such attaching means as shown in the drawings may be rivets. To the rear part of lever 8, is pivoted a wheel supporting lever 9 which is pivotally supported by stud 10 attached to the scoop. The wheels which support the lever 9 are mounted upon an 30 axle 11 which is securely fixed at its middle point to the end of lever 9. The wheels 12 on the ends of axle 11 may be of any desired form or size. The wheels 12 through levers 9 and 8 act upon the scoop blade 5 to deflect 35 it when the scoop is passing over rough or uneven surfaces. To control the motion of the scoop blade 5, the following specific hinge structure has been devised. In Figure 5 two of such hinges are shown connected to the scoop blade and the scoop. These 40 hinges are shown to be in two parts pivotally connected together, one part 13 securely attached to the scoop blade by rivets 14, the other part 15 slidably connected to 45 the scoop by guides 16. On the rear end of the sliding part of the hinge is a projection 17 having an opening through which a longitudinal spring member 19 passes. The 50 spring member 19 is supported and carried by brackets 18 securely attached to the under side of the scoop. It is preferable that the bracket 18 securely engage and hold the longitudinal spring 19, but all these brackets except the end brackets, may be permitted to 55 engage the spring to allow a slight longitudinal movement thereof when the spring is bent due to the movement of the scoop blade. Under normal conditions, that is when the 60 scoop blade and scoop are in line, the longitudinal spring is straight, but should the 65

blade be moved up or down the spring will be bent either forward or backward due to the sliding of the part 15 of the hinge in the guide 16. Figure 9 shows how the spring is bent when the scoop blade is deflected upward. The longitudinal spring under normal conditions will maintain the scoop blade in line with the scoop and is sufficiently strong to effect this purpose. But should the blade come in contact with any obstruction the spring 19 will yield so the blade will accommodate itself to resisting obstruction. This specific scoop structure, clearly shown in Figures 5 and 6, has the advantage of always permitting the scoop blade to properly clean the surface and move at a proper distance therefrom regardless of the uneven nature of the surface. When the front end of the scoop passes over an elevation or bump in the surface, either the runners 5 70 or the wheels 12 will engage the uneven surface and bend the scoop blade causing it to rise over said surfaces. If it were not for this specific structure of scoop blade, permitting the deflection thereof, the scoop might become permanently injured by contacting with some rough or uneven surface. Though this structure of blade and blade connection permits the scoop to pass over obstructions without injury thereto, yet the specific form of hinges and spring shown 75 guarantee that the blade will always be held in working relation to the surface and in scooping condition due to the force of the spring and the particular construction of the hinges. 80

The structure of the hinges and the springs for the snow wings are in all respects similar to that of the spring and hinges for the snow blade. 95

Figure 7 shows the snow blade and the scoop in normal aligned position while Figure 8 shows the snow blade deflected upward and the longitudinal spring bent. The bent position of the spring is shown in Figure 9. The spring 19 as shown in Figures 8 and 9 pulls on the sliding part of the hinge and tends to bring the blade back in line with the scoop. 100

For the purpose of operating the snow wings to direct the snow to both chutes or to the chute on any one side of the machine the following mechanism is provided. Each wing has its own means of operation and is similar to the other one in every respect. Hand wheels 20 through gear mechanism 20' operate longitudinal shafts 21 which have on the ends thereof arms 22. The arms 22 are connected by links 23 to the snow wings 6. It will thus be seen that by rotating the hand wheels 20, the snow wings may be adjusted at any desired angle to the scoop. 110

For the purpose of elevating or lowering the snow chutes, each chute is provided with a rack bar 24 which meshes with a pinion 25. 120

The pinions 25 are operated by a hand wheel 26 through suitable gears 27 and shaft 28 on the ends of which the pinions 25 are located. The chutes 4 are connected to the frame by hinge means 7 shown in Figure 12. The hinges 7 through the above described adjusting means permit the chutes to be elevated or lowered at such angle as the operator desires.

10 On the outer end of each chute a foldable snow deflector 29 is provided. This deflector is composed of sections which in folded position overlie each other as is clearly shown in Figures 3 and 4. The deflector in 15 open position is shown in Figure 13. Any suitable means may be used for connecting the sections of the deflector. In the present illustration, there is shown a strap 29'. The sections of the deflector are pivoted to each 20 other and to the chute as is clearly shown in Figures 13 and 14. For operating the deflectors, open and close the sections, a system of levers and links is provided as shown in Figure 13. A hand lever 30 is pivoted to 25 the chute 4 and has pivotedly connected thereto link 31 which operates link 32 pivotedly mounted upon the chute 4. Attached to the end of link 32 opposite to the attachment of link 31, is a second link 33 extending 30 from link 32 to an arm 34 extending from the outer section of the deflector.

Figure 15 shows a modified form of scoop in which the scoop blade and the snow wings are attached to the scoop proper by ordinary hinges. The supporting structure of this modified form is similar to that of the principal form shown in Figure 2 with the exception of the specific form of hinge and spring.

Having described my invention, what I claim as new and desire to secure by Letters Patent is:

1. In a snow machine, a scoop, snow cutting means connected with the scoop and having roller supporting means for deflecting said means with relation to the scoop.

2. In a snow machine, a scoop, a blade on said scoop, a hinge rigidly connected with the blade and slidably connected to the scoop.

3. In a snow machine, a scoop, a blade associated with the scoop, a hinge having one member rigidly attached to the blade and the other member slidably attached to the scoop and spring means for controlling the sliding member of the hinge.

4. In a snow machine, a scoop, a blade associated with the scoop, a hinge member having one part rigidly attached to the blade and the other part slidably attached to the scoop member and a rod spring attached to the scoop member and engaging the sliding part of the hinge to control the blade,

5. In a snow machine, a V-shaped scoop member, a chute on each side of the machine, and a circular shaped snow wing pivotally mounted on each side of the scoop member and adapted to be adjusted to direct the snow to both of the chute members or to either one of them and to give the snow a rolling movement as it advances up the scoop member. 70

6. In a snow machine, snow scooping means, a blade pivotally mounted to the scooping means, wheel means attached to the blade and adapted to engage the surface for deflecting the blade. 75

7. In a snow machine, a snow scoop associated therewith, a blade pivotally mounted on the scoop, and a hinge member pivotally connecting the scoop and the blade, one element of the hinge member being rigidly attached to the blade and the other element 80 thereof being slidably attached to the scoop.

8. In a snow machine, a scoop member, a blade pivotally attached to the scoop member, a hinge member pivotally connecting the scoop member and the blade, one element of the hinge member being rigidly attached to the blade and the other slidably attached to the scoop member and spring means for controlling the sliding movement of the slidable element of the hinge. 90

9. In a snow machine, a scoop member, a hinge element slidably connected to the scoop member, a blade rigidly attached to the hinge element, a lever secured to the blade and means attached thereto for oscillating the blade by means of the hinge member. 100

10. In a snow machine, a scoop member, a hinge member having one element thereof slidably attached to the scoop member, a blade rigidly attached to the other element of the hinge member, a lever attached to the blade and a second lever attached to the first named lever for deflecting the blade. 105

11. In a snow machine, a scoop member, a hinge member having one element thereof slidably attached to the scoop member, a blade rigidly attached to the other element of the hinge member, a lever attached to the blade, a second lever attached to the 115 first named lever for deflecting the blade, and a spring member for controlling the sliding movement of the sliding hinge element.

12. In a snow machine, a V-shaped scoop member, a circular shaped snow wing on each side of the scoop member and adapted to give the snow a rolling and compacting motion as it advances up the chute, and chute means for receiving the snow from 125 the scoop member and depositing it on either or both sides of the snow machine.

13. In a snow machine, a V-shaped scoop member, a circular shaped snow wing on each side of the scoop member adapted to 130

give the snow a rolling motion and adapted to direct the snow to either or both sides of the machine in a substantially round and compact snow thread.

14. In a snow machine, a V-shaped scoop member, thereon, chute members associated with the machine and circular shaped snow wing attached to the scoop member and adapted to direct the snow into either or both of the chute members and to give the snow a rolling and compacting motion as the snow advances toward the chutes.

15. In a snow machine, a V-shaped scoop member thereon, a circular shaped snow wing on each side of the scoop member, a tubular shaped chute on each side of the machine, said snow wings being adapted to be adjusted so as to direct the snow in either one of the chute members in a circular snow thread of the same size and shape as that of the chute member.

16. In a snow machine, a scoop member, a circular shaped snow wing pivotally mounted on each side of the scoop member and adapted to direct the snow as it passes up the scoop member, an operator's cab and means in the cab by which the said snow wings may be rotated to direct the snow.

17. In a snow machine, a V-shaped scoop member, a circular shaped snow wing pivotably mounted on each side of the scoop member and adapted to direct the snow up the scoop member, a chute member on each side of the machine and adapted to receive

the snow from the scoop member, an operator's cab, means operable from the cab to rotate said wings and means operable from the cab to elevate or lower the chute members.

18. In a snow machine, a chute on each side of the machine, means for receiving and directing the snow to the chutes, a deflector on one end of each chute, an operator's cab and means operated from the cab to raise and lower the chute member and means operable from the cab to operate the deflectors.

19. In a snow machine, a chute on each side of the machine, snow receiving means associated therewith, wing means on each side of the snow receiving means and adapted to direct the snow to either or both of the chutes, means associated with the chutes by which they may be raised or lowered and deflector means on each chute and lever means for operating the deflectors.

20. In a snow machine, chutes associated therewith, a deflector on each chute, an operator's cab on said machine, means for adjusting the chutes, means for adjusting the deflector, both said means being operated from said cab and a snow receiving and directing means adapted to receive and direct the snow to either or both of the said chutes.

In testimony whereof I affix my signature.

LANK HUGHES.
